WITNESS:

H. J. Belcher

INVENTOR

BY *Victor J. Evans*

ATTORNEY

UNITED STATES PATENT OFFICE.

HAROLD JOS. BELCHER, OF ALGIERS, LOUISIANA.

FLUSH VALVE.

Application filed December 10, 1923. Serial No. 679,717.

To all whom it may concern:

Be it known that I, HAROLD JOS. BELCHER, a citizen of the United States, residing at Algiers, in the parish of Orleans and State 5 of Louisiana, have invented new and useful Improvements in Flush Valves, of which the following is a specification.

This invention relates to devices for flushing toilets and the like and has for its object 10 the provision of a novel valve structure which, when opened, will remain open a predetermined length of time to permit flow of water, the device embodying a motor for returning the parts to initial position to 15 discontinue the flow.

An important object is the provision of a 20 control valve mechanism of this character which will eliminate use of the ordinary and well known tank and be far more slightly than the usual construction especially as 25 the device may be easily concealed within a wall at the time the plumbing fixtures are installed.

Another object is the provision of a 30 mechanism of this character which is provided with adjusting means whereby the length of time during which water will flow may be varied to meet different conditions.

An additional object is the provision of a 35 device of this character which will be simple and inexpensive to manufacture and install, easy to operate, efficient in use, durable in service, and a general improvement in the art.

With the above and other objects and advantages in view, the invention consists in the details of construction to be hereinafter more fully described, and claimed, and illustrated in the accompanying drawings, in 40 which:

Figure 1 is an elevation of the device.

Figure 2 is an elevation taken at right angles to Figure 1, the wall being in section.

Figure 3 is a section taken longitudinally 45 through the motor and inlet valve construction.

Figure 4 is a horizontal section on the line 4-4 of Figure 1.

Figures 5 and 6 are detail views of the 50 clutch element.

Figure 7 is a detail sectional view through the motor member.

Referring more particularly to the drawings, the letter A represents a wall within 55 which the device is installed and B indicates a water inlet pipe, while C represents

the water outlet pipe which leads to a closet bowl or the like.

In carrying out my invention, I provide a casing designated broadly by the numeral 60 10 and including a relatively large lower portion 11 and an upper portion 12 which is formed partially cylindrical for containing a water motor including a hub 13 carried by a shaft 14 and equipped with radial arms 15 at the ends of which are mounted paddles or buckets 16. Extending into one side of the upper portion 12 of this casing is an inlet pipe 17.

The numeral 18 represents the casing of a 70 control valve device, which casing is connected with the pipes B and 17, and this casing is provided internally with a seat 19 normally closed by a valve 20 carried by a stem or plunger 21. Within the casing 18 is a coil spring 22 which engages against the valve 20 for the purpose of normally holding it against its seat. However, this valve is preferably of such construction that the 75 water pressure itself will tend to hold it closed. It should be stated that the plunger 21 is slidable through a suitable packing gland 23 at the end of the cap 24 which closes one end of the casing 18. The plunger projects considerably beyond the packing 80 gland and has its terminal rounded as shown.

Mounted over an opening D in the wall structure A is a plate or disk 25 which forms a closure for this opening and which 90 also forms one bearing for an operating shaft 26 which is also journaled in a step bearing 27 on the front of the casing portion 12. At its outer end this control shaft 26 carries a handle 28 which is movable to 95 effect opening of the valve by means to be described.

Rotatable upon the shaft 26 is a sleeve 29 which is provided at one end with a crank arm 30 pivotally connected at 31 with a link 100 32 which is pivoted at 33 upon the free end of a lever 34 which has its other end pivoted at 35 upon a bracket 36 carried by the cap 24 of the valve structure 18. On the shaft 26 is a pin 26a adapted to engage a pin 29a on 105 the sleeve 29. By grasping the handle 28 and turning it to the left, it is quite obvious that the lever 34 will be swung and will press the plunger 21 inwardly to unseat the valve 20 and permit water to flow through the pipe 110 17 into the motor.

In order to hold the parts in this position

to permit water to flow for a certain length of time, I provide a ratchet 37 which is carried by the sleeve 29 and with which cooperates a tooth 38 on the lower edge of an elongated bar 39 which is suitably pivoted at 40 upon the casing. When the handle is turned, it is quite apparent that the engagement of the tooth 38 with one of the teeth of the ratchet will operate to hold the parts 29, 30, 10 32 and 34 against returning movement until the bar 39 is actually disengaged by the means to be described, it being apparent, however, that the handle 28 may drop down and restore the shaft 26 to initial position.

15 Suitably journaled at the outside of the casing is a shaft 41 equipped at one end with a worm wheel 42 with which meshes a worm 43 on the lower end of a vertical shaft 44 journaled in suitable bearings and carrying 20 a worm wheel 45 meshing, in turn, with a worm 46 on a stub shaft 47. Also mounted on this stub shaft and rotatable with the worm 46 thereon is a gear 48 which meshes with a pinion 49 on the motor shaft 14. Rotatably mounted upon the shaft 41 at the end thereof most remote from the worm 43, is a pinion 50 carrying a clutch element 51 adapted to be engaged by a coacting clutch element 52 carried by a grooved collar 53 25 splined on the shaft 41. For normally urging the two clutch elements into coacting engagement, I provide a coil spring 54 which encircles the shaft 41 and which has one end abutting against the collar 53 and its other 30 end engaging against a stop collar 55.

35

Mounted on the casing are guides 56 through which is slidably an elongated rack bar 57 meshing with the pinion 50 and normally urged into lowered position by means 40 of a coil spring 58 which encircles the rack bar and which bears against the lowermost guide 56 and against a head 59 at the lower end of the bar. This rack bar is so positioned that when it is raised it will strike 45 against the bar 39 and lift it so as to release the tooth 38 from engagement with the ratchet 37 and permit the spring valve 20 to close. In order to permit variation in the time during which water will flow, I provide a screw 60 which is engaged with the upper end of the rack bar 57 and which has its head designed to engage with the bar 39. It is quite apparent that by screwing 50 this screw in or out as the case may be, the time required for the rack bar to reach and lift the bar 39 may be varied.

55 The clutch control means comprises a shifting fork 61 which is pivoted at 62 and which has one end engaged with the grooved collar 53. Pivottally connected at 63 with the other end of this shifting fork is a link 64 which is in turn pivottally connected with a crank arm 65 depending from and secured to the operating shaft 26.

60 65 In the operation of the device it will be

seen that ordinarily the valve 20 is closed so that water cannot pass through the casing 18 to the motor structure. It is also true that the pressure of the spring 22 of the valve structure holding the plunger 21 70 against the lever 34 will operate to hold the shaft 26 at one limit of its movement and with the shifting fork 61 in such position that the clutch elements 51 and 52 will be engaged. At this time the rack bar 57 is at 75 its lowermost position and retained there partly by gravity and partly by the action of the spring 58.

Whenever it is desired to effect flushing, 80 it is necessary to grasp the handle 28 and turn it to the left, whereupon the engagement of the pins 26^a and 29^a will cause turning movement of the sleeve 29 and the crank arm 30 will move the lever 34 and press the plunger 21 inwardly to unseat the 85 valve 20. When this is done water flows through the valve seat 19 and through the pipe 17 into the casing of the motor and the result will be that the motor will be driven while the water discharging therethrough 90 will pass into the lower portion 11 of the casing and out through the pipe C to the bowl. After moving the handle to start the operation, it is intended that the handle be 95 quickly released so that it may return to normal position.

When the handle is turned as above described, it is apparent that the ratchet 37 will ride under the tooth 38 and that this tooth will prevent retrograde movement. 100 In addition to unseating the valve, the initial movement of the handle 28 results in swinging the fork 61 upon its pivot 62 so that the clutch element 52 will be disengaged from the clutch element 51, while the dropping back of the handle reengages the clutch. 105 The rotary movement of the motor is imparted to the gear 48 which in turn drives the gearing and causes rotation of the shaft 41. When the clutch element 52 is in engagement with the element 51, it is apparent that the pinion 50 will be locked for rotation with the shaft 41 so that as the pinion continues to rotate the rack 57 will be moved 110 upwardly. When the rack reaches the upper limit of its movement the screw 60 carried thereby will engage beneath the free end of the bar 39 and lift the latter so as to withdraw the tooth 38 from its engagement with the ratchet. 115 The moment the tooth 38 is lifted it is apparent that the pressure of the spring 22 in the valve structure will operate to return the parts except the rack to normal position in which they will remain until the lever or handle 28 is again swung to effect flushing. The rack is not lowered until the handle is again lifted or turned to effect a subsequent flushing, whereupon 120 the disengagement of the clutch permits the rack to drop down.

From the foregoing description and a study of the drawings, it is apparent that I have thus provided a novel flush control device which is manually released but which 5 automatically resets itself after water has flowed for a predetermined length of time. The device is entirely automatic in action except for the manual release and will require no personal attention. A distinct feature of advantage is that this mechanism will 10 obviate the use of the wellknown tank which occupies considerable space on the wall and which is more or less unsightly. The present device is readily adapted to be built into a 15 wall during the construction of a building or during the installation of the plumbing fixtures, and there is nothing visible except the operating handle.

While I have shown and described the 20 preferred embodiment of the invention, it is to be understood that I reserve the right to make such changes in the form, construction and arrangement of parts as will not depart from the spirit of the invention 25 or the scope of the subjoined claims.

Having thus described the invention, what is claimed:

1. In a device of the character described, the combination of a casing having an inlet 30 and an outlet, a rotary paddle wheel journaled within the casing adjacent said inlet, a valve device interposed between said inlet and a source of supply including a body having a seat, a valve normally closing said seat and having an operating plunger, a pivoted 35 lever engaging said plunger, a shaft having a crank connection with said lever, a handle on said shaft, catch means for holding said shaft against retrograde movement subsequent 40 to rotation thereof, and means driven by said paddle wheel for releasing said catch means, said means having a longitudinally movable rack bar, a shaft having a driving connection with the shaft of the paddle 45 wheel, a pinion rotatable on said last named shaft and meshing with said rack, clutch means on said last named shaft engageable with the pinion for locking the same for rotation with the shaft, and means connected 50 with said handle and said clutch for throwing the same into and out of gear.

2. In a device of the character described,

the combination of a casing having an inlet and an outlet, a rotary paddle wheel journaled within the casing adjacent said inlet, a 55 valve device interposed between said inlet and a source of supply including a body having a seat, a valve normally closing said seat and having an operating plunger, a pivoted lever engaging said plunger, a shaft having a crank connection with said lever, a handle on said shaft, catch means for holding said shaft against retrograde movement subsequent 60 to rotation thereof, means driven by said paddle wheel for releasing said catch means, said means having a longitudinally movable rack bar, a shaft having a driving connection with the shaft of the paddle wheel, a pinion rotatable on said last named shaft and meshing with said rack, clutch 65 means on said last named shaft engageable with the pinion for locking the same for rotation with the shaft, means connected with said handle and said clutch for throwing the same into and out of gear, including a shifting fork operatively connected with said clutch member, a crank on the first named shaft, and a link connection between said crank and said shifting fork.

3. In a device of the character described, a 70 casing having an inlet and an outlet, a rotary paddle wheel journaled within said casing, a spring closed valve interposed between said inlet and a source of supply, said valve having an operating plunger, a pivoted lever 75 engaging said plunger, an operating shaft equipped with a handle and having a crank connection with said lever, a ratchet on said shaft, a pivoted arm having a tooth engaging with said ratchet, a rotary shaft driven by said paddle wheel, a clutch splined upon said shaft, a pinion rotatable on said last named shaft and carrying a clutch member, a longitudinally 80 slideable rack bar meshing with said pinion, a movable fork engaging the first named clutch element, and having a crank connection with said operating shaft, said rack being movable to engage said arm and lift the tooth from engagement with the ratchet.

In testimony whereof I affix my signature.

HAROLD JOS. BELCHER.
